CORPORATION OF DELAWARE.

IRONING-MACHINE.

No. 804,949.

Specification of Letters Patent.

Patented Nov. 21, 1905.

Application filed May 26, 1903. Serial No. 158,782.

To all whom it may concern:

Be it known that I, ROBERT CLARENCE HOLLIS, a citizen of the United States, residing in Wilmington, in the county of New Castle and State of Delaware, have invented certain new and useful Improvements in Ironing-Machines, of which the following is a true and exact description, reference being had to the accompanying drawings, which form a part thereof.

My invention relates to ironing-machines, and is especially adapted and intended for use in finishing the bent edge of turned-over collars, although it is adapted for use with any article which requires an edge to be nicely ironed and finished and has been successfully applied to finishing the edge of "stand-up" collars.

The object of my invention is to provide an ironing-machine especially well adapted to finish the edge of collars or other articles and also to provide convenient and effective improvements for giving the proper curvature to a collar or like article.

The nature of my improvements will be best understood as described in connection with the drawings, in which they are illustrated, and in which—

Figure 1 is an end elevation of the machine in what I believe to be its best form; Fig. 2, a side elevation thereof; Fig. 3, a cross-sectional view on the line 3 3 of Fig. 2, showing the plies of a turned-over collar in position on the machine. Fig. 4 is a plan view of a portion of a turned-down collar in the condition in which it is prepared for ironing on my machine. Fig. 5 is a similar view showing the collar folded over and ready for insertion. Fig. 5^a is a detail of the guide-plate in plan view. Fig. 6 is an end elevation of a machine embodying my invention in modified form; Fig. 7, a side elevation of said machine, and Fig. 8 a perspective view of the iron and guide-plate of said modified machine.

Referring first to the machine of Figs. 1 to 5^a, A and A' indicate the framings which support the mechanism. Each of these frame portions is provided with slotted guideways, (indicated at A² and A³), the guideways extending through the frame at the top and being closed by cap-pieces, (indicated at A⁴

and A⁵.) The framing A is provided with a bracket A⁶, extending out from it, as shown, and the framing A' has an inwardly-extending portion A⁷, which supports pivot-lugs, (indicated at A⁸.) B, B', and B² indicate shaft-bearings movable vertically in the guideways A² and A³; these bearings, like the guideways A² and A³, being duplicated in each frame portion A and A'. The bearings B are adjustably supported on adjusting-screws, (indicated at C), and the bearings B' are supported through springs, such as are indicated at C', on the bearings B, adjusting screws C² serving to determine the position of the upper bearings. The bearings B² are supported on springs, such as are indicated at C³, and are adjusted to position by means of set-screws, such as are indicated at C⁴. D is a shaft supported by the bearings B and having at one end the fast and loose pulleys, (indicated at E and E'). D' is a shaft supported by the bearings B' and driven at the same speed and in opposite direction to the shaft D through the gear-wheels, (indicated at F and F'). D² is a shaft supported by the bearings B² and preferably driven from the shaft D', as shown by the gear-wheels K and K' or in any convenient manner. d and d' are feed-rolls secured on the shafts D and D', and d² is a bending-roll secured on the shaft D². G is a guide-plate supported on the bracket A⁶ and having an edge G' directed toward the bite of the rolls d and d', the inner portion of the guide-plate (indicated at G²) preferably extending, as shown in Fig. 3, between the feed-rolls H is an iron, preferably having a concave operative surface, as indicated at H', so placed as to operate in connection with the edge G' of the guide-plate. The iron is, as shown, hollowed out at H² and supported on an arm H³, pivoted to the lugs A⁸ at H⁴ and having, preferably, a stop-lug H⁵, which by abutting against a portion of the frame A⁷ will prevent the iron from moving too far inward. The arm H³ is shown as provided with an outwardly-extending arm H⁶, acted on by a spring I, which tends to keep the front pressed toward the edge G' of the guide-plate. J is a gas-pipe having a cock J' and connecting to a Bunsen burner, (indicated at J²), the burner being supported, preferably, on the arm H³ and directed into the hollow

portion H^2 of the iron. At L, I have indicated the collar, the inner fold being indicated at l' , the outer fold or face of the collar at l , and the top or bent portion at l^2 . In practice the rolls are in operation, as shown by the arrows in Fig. 3, and where a turned-down collar is to be finished the collar having been first ironed in the flat, the portion to be bent—to wit, l^2 , Fig. 4—is damped and the collar then folded over, as indicated in Fig. 5. The folded collar is then passed over the plate G, with the inside of its folded-over edge against the edge G' , and as the collar is fed forward by the feed-rolls d and d' its folded-over edge is ironed by the concave portion H' of the iron, and as the collar issues from between the feed-rolls it is deflected upward by the guide-roll d^2 , which can be adjusted so as to give any desired curvature to the finished collar. It will be understood that the guide-plate G shall be smoothly finished on top and bottom, so as to offer as little frictional resistance to the passage of the collar over it as possible, and it is highly advantageous that this guide-plate should extend between the feed-rolls, as in this way the too sharp bending of the collar at the crease is avoided. By the expressions "means for feeding" and "feed mechanism" as employed in the claims I intend to be understood as including the feed-rolls d d' or any other equivalent feed mechanism. In this construction illustrated, where the plate G extends practically into contact with the feed-rolls, the said plate will act to hold the collar or other article to be ironed in contact with either of the feed-rolls shown, thus enabling it to make proper frictional contact with the collar and to feed it forward irrespective of the presence of the other feed-roll.

In the machine of Figs. 6 to 8 *a* indicates the framing, in bearings on which are supported the shafts D D', geared together by gears f f' and supporting feed-rolls d^3 d^4 . *g* is the guide-plate, which in this case is placed on the delivery side of the feed-rolls and supported on an arm *m*, which is in turn supported on the cylindrical rod *a'* and secured thereto by a set-screw *n*. The iron *h* is supported in a guideway on an arm *h*³, supported by rod *a'* and shaft D, and is pressed in toward the edge *g'* of plate *g* by a spring *i*, supported on an arm *h*⁴, which extends from a rod *h*⁴, as shown. An adjustable arm *m'*, secured on rod *a'* by set-screw *n'*, supports the bending-guide *o*, which in this case lies in front of the feed-rolls. In operating this modified machine the collar or other article is fed to the feed-rolls d^3 d^4 over the bending plate or guide *o* and in such manner that, if a standing collar, it will pass over or, if a folded collar, both over and under the guide-plate *g*, the edge to be ironed resting against the iron *h* along its concave face *h'*, and it will be seen that the article will in this machine as in the

other have the edge l^2 ironed and also receive a curvature, such as is desired in collars and cuffs.

Having now described my invention, what I claim as new, and desire to secure by Letters Patent, is—

1. An ironing-machine having in combination means for feeding the article to be ironed, a guide-plate having an edge extending parallel to the line of feed, and an iron arranged to coact with the edge of the guide-plate. 70

2. An ironing-machine having in combination means for feeding the article to be ironed, a guide-plate having an edge extending parallel to the line of feed, and an iron having a concave face arranged to coact with the edge of the guide-plate. 80

3. An ironing-machine having in combination means for feeding the article to be ironed, a guide-plate having an edge extending parallel to the line of feed, an iron arranged to coact with the edge of the guide-plate, and a bending-guide arranged in such relation to the feed mechanism and the iron and guide-plate as to cause the articles being ironed to move through a curved path. 85

4. An ironing-machine having in combination means for feeding the article to be ironed, a guide-plate having an edge extending parallel to the line of feed, an iron arranged to coact with the edge of the guide-plate, and an adjustable bending-guide arranged in such relation to the feed mechanism and the iron and guide-plate as to cause the articles being ironed to move through a curved path. 95

5. An ironing-machine having in combination feed mechanism, a guide-plate having an edge extending in front of the feed mechanism so as to receive the article to be ironed in advance of its engagement with the feed, and an iron also situated in advance of the feed and coacting with the edge. 100

6. An ironing-machine having in combination feed mechanism, a guide-plate G, having an edge G' , extending in front of the feed mechanism so as to receive the article to be ironed in advance of its engagement with the feed, an iron also situated in advance of the feed and coacting with the edge G' , and a bending-guide situated on the rear of the feed mechanism. 110

7. An ironing-machine having in combination feed mechanism, a guide-plate G, having an edge G' , extending in front of the feed mechanism so as to receive the article to be ironed in advance of its engagement with the feed, an iron also situated in advance of the feed and coacting with the edge G' , and a bending guide-roll situated at the rear of the feed mechanism. 120

8. An ironing-machine having in combination feed mechanism, a guide-plate G, having an edge G' , extending in front of the feed mechanism so as to receive the article to be ironed in advance of its engagement with the feed mechanism. 125

- feed, an iron also situated in advance of the feed and coacting with the edge G', and a bending guide-roll positively actuated, situated on the rear of the feed mechanism.
- 5 9. An ironing-machine having in combination feed-rolls a guide-plate having an edge extending at right angles with the line of bite of the feed-rolls, and an iron arranged to coact with the edge of the guide-plate.
- 10 10. An ironing-machine having in combination feed-rolls, a guide-plate having an edge extending at right angles with the line of bite of the feed-rolls and an iron having a concave face arranged to coact with the edge 15 of the guide-plate.
11. An ironing-machine having in combination feed-rolls, a guide-plate having an edge extending at right angles to the line of bite of the feed-rolls, an iron arranged to coact with the edge of the guide-plate, and a bending-guide arranged in such relation to the feed-rolls and the iron and guide-plate as to cause the articles being ironed to move through a curved path.
- 25 12. An ironing-machine having in combination feed-rolls, a guide-plate having an edge extending at right angles to the line of bite of the feed-rolls, an iron arranged to coact with the edge of the guide-plate, and an adjustable bending-guide arranged in such relation to the feed-rolls and the iron and guide-plate as to cause the articles being ironed to move through a curved path.
- 30 13. An ironing-machine having in combination feed-rolls d, d', a guide-plate G, having an edge G', extending in line with the bite of the feed-rolls and substantially perpendicular thereto, and an iron arranged in front of the feed-rolls and coacting with the 35 edge G', of the plate G.
- 40 14. An ironing-machine having in combination feed-rolls d, d', a guide-plate G, having an edge G', extending in line with the bite of the feed-rolls and substantially perpendicular thereto, and an iron arranged in front of the feed-rolls and having a concave face H', coacting with the edge G', of plate G.
- 45 15. An ironing-machine having in combination feed-rolls d, d', a guide-plate G, extending in front of and between the feed-rolls, said plate having an edge G', extending in line with the bite of the feed-rolls and
- substantially perpendicular thereto, and an iron arranged in front of the feed-rolls and coacting with the edge G', of plate G. 55
16. An ironing-machine having in combination feed-rolls d, d', a guide-plate G, having an edge G', extending in line with the bite of the feed-rolls and substantially perpendicular thereto, an iron arranged in front of the feed-rolls and coacting with the edge G', of plate G, and a bending-guide lying in the rear of the feed-rolls. 60
17. An ironing-machine having in combination feed-rolls d, d', a guide-plate G, having an edge G', extending in line with the bite of the feed-rolls and substantially perpendicular thereto, an iron arranged in front of the feed-rolls and coacting with the edge G', of plate G, and a bending guide-roll lying in the rear of the feed-rolls. 65
18. An ironing-machine having in combination feed-rolls d, d', a guide-plate G, having an edge G', extending in line with the bite of the feed-rolls and substantially perpendicular thereto, an iron arranged in front of the feed-rolls and coacting with the edge G', of plate G, and a bending guide-roll positively actuated lying in the rear of the feed-rolls. 70
19. In a machine of the character described, the combination with a guide-plate and a coöperating grooved ironing-shoe, of a roller adjacent to said guide-plate operating to feed the collar over said guide-plate and through a groove of said shoe. 75
20. An ironing device, comprising a fixed collar-support, an iron movable toward and from said support, means for forcing said iron toward the support to press the folded collar 90 thereon, means for drawing the collar through the ironing device, and means for heating the iron. 80
21. An ironing device, comprising a thin fixed collar-support, an iron having an arched 95 passage-way that engages the collar-support saddlewise, means for pressing the iron upon the collar yieldingly, means for heating said iron, and means for seizing and drawing the collar through the iron.
